UNITED STATES PATENT OFFICE

149,647

DESIGN FOR A COMBINED IRON REST AND
CORD TAKE-UP

Louis W. Jones, Cleveland, Ohio

Application August 19, 1946, Serial No. 132,637

Term of patent 3½ years

(Cl. D49—6)

To all whom it may concern:

Be it known that I, Louis W. Jones, a citizen of the United States, residing at Cleveland, in the county of Cuyahoga and State of Ohio, have invented a new, original, and ornamental Design for a Combined Iron Rest and Cord Take-Up, of which the following is a specification, reference being had to the accompanying drawing, forming a part thereof.

Figure 1 is a side elevational view of a combined iron rest and cord take-up embodying my new design;

Fig. 2 is an end elevational view, as seen from the right of Fig. 1;

Fig. 3 is a top plan view; and

Fig. 4 is a bottom plan view thereof.

I claim:

The ornamental design for a combined iron rest and cord take-up, as shown.

LOUIS W. JONES.
